UNITED STATES PATENT OFFICE.

EMMOR J. STEWART, OF NEW YORK, N. Y.

FLOOR-CLEANING MACHINE.

1,233,822.

Specification of Letters Patent. Patented July 17, 1917.

Application filed February 24, 1914, Serial No. 820,394. Renewed July 24, 1916. Serial No. 111,056.

To all whom it may concern:

Be it known that I, EMMOR J. STEWART, a citizen of the United States, and a resident of the borough of Manhattan, in the city, county, and State of New York, have invented certain new and useful Improvements in Floor-Cleaning Machines, of which the following is a specification.

My improvements relate to the type of 10 floor cleaning apparatus set forth in Letters Patent No. 853,525, issued to me May 14th, 1907, and Letters Patent No. 1,128,384 issued to me February 16, 1915, in which an electrically driven scrubbing brush is rotated 15 in a direction opposite to that of the line of travel, which latter may be reversed without turning the apparatus around.

The present invention relates to the construction and arrangement of parts herein 20 described and claimed specifically, whereby the motor and operative parts are supported on side frames independent of the reversible activity levers, whereby the splash aprons are cleaned, and whereby the construction and operation of the apparatus is 25 simplified, stabilized and rendered most effective.

In the accompanying drawings,

Figure 1, is a top view of my improved 30 floor cleaning apparatus, the handle and portions of the side levers being omitted in part;

Fig. 2, an end view thereof;

Fig. 3, a side view;

Fig. 4, a transverse central vertical sectional elevation;

Fig. 5, a sectional elevation upon plane of line 5—5^a, Fig. 4, looking in the direction of the arrow 5^x.

Fig. 6, a sectional elevation upon plane of line 5—5^a, Fig. 4, looking in the direction of the arrow 6^x.

Fig. 7, a sectional elevation upon plane of line 7—7 Fig. 4, looking in the direction 45 of the arrow 7^x.

Fig. 8, a sectional elevation showing modifications in the construction;

Fig. 9, is a sectional detail of the side lever shown in Fig. 7;

Fig. 10 is a detail showing means for holding down the depression rod by which the liquid valves are operated;

Fig. 11, a sectional detail of the opposite side lever, showing upon an enlarged scale 55 the axial structure;

Fig. 12, is a sectional detail showing means for adjusting the motor platform;

Fig. 13, is a sectional detail showing the method of supporting the splash aprons.

In the drawings for convenience and simplicity the machine is shown in the medial or upright position resting on the central traction rollers only. In use the machine is slightly inclined in one direction or the other, resting upon said central traction 60 rollers and the caster traction rollers at one end or the other of the machine. This slight inclination in use is provided for the purpose of lowering the advance apron into contact with the floor, or nearly so, in order 65 that the spatter from the brush may be fully collected and diverted into the forward receiving compartment.

The side members *a*, *a*^x, of the frame are united by a platform *b*, having drop or 70 bracket flanges *b'*, *b'*, upon and between which the brush *B*, is mounted in bearings *b*², *b*². The motor *M*, is mounted upon the platform *b*, and is connected with and actuates the brush *B*, through the medium of the 75 sprocket chain *m*, and sprocket gears *m'*, and *b*³, the latter being mounted on the brush shaft and the former *m'*, on the motor shaft. The motor *M*, and brush *B*, being thus mounted and connected in permanent 80 relationship to each other, such relationship will not be affected by the adjustment of the platform *b*, upon the side members *a*, *a*^x, for the purpose of regulating the position 85 of the brush *B*, with relation to the surface 90 to be treated. This vertical adjustment of the brush is effected by adjusting the platform *b*, upon the side members *a*, *a*^x, by any suitable means as may be found most expedient. Thus in the construction shown in 95 the drawings the side members *a*, *a*^x, are formed with vertically elongated slots *a'*, *a'*, through which pass screw studs *b*⁴, *b*⁴, projecting from the bracket flanges *b'*, *b'*, or the platform *b*, the nuts *b*⁵, *b*⁵, which engage 100 with the outer threaded ends of the studs *b*⁴, *b*⁴, bearing against the outer surfaces of the side members *a*, *a*^x, and affording means 105 whereby the platform may be secured in a prescribed position. Obviously the screw studs *b*⁴, *b*⁴, might be threaded bolts screwing into the platform, the heads of the bolts performing the same function as the nuts *b*⁵, *b*⁵.

The side frames *a*, *a*^x, are each provided 110

with three bearing rollers, a central one a^2 , mounted by preference in a recess in the bottom edge of the side member, and on which the frame rests under all conditions of use, 5 and end caster rollers a^3 , a^3 , mounted on extension arms a^4 , a^4 ,—it being understood that the apparatus is reversible so that the caster rollers a^3 , a^3 , will be alternately front or rear bearing rollers according to the direction in which the apparatus is propelled. 10 The caster rollers a^3 , a^3 , are also so mounted on the extensions a^4 , a^4 , as to rest on the floor only alternately as the frame is rocked in either direction upon the central rollers 15 a^2 , as a fulcrum. This rocking or tilting of the frame is effected through the medium of the side levers c , c' , which also afford means whereby the machine may be propelled in either direction,—said levers being 20 pivotally attached to the side members as at c^2 , and the side members being formed with stops a^5 , a^5 , which limit the swing of the levers in either direction.

The side levers c , c' , are rigidly connected 25 at or near their upper extremities by a cross member c^3 , which acts as the handle of the machine. The cross bar c^3 , and the main portion of each side lever c , c' , are hollow, metallic tubes being preferably used for the 30 purpose. In the case of the side levers c , c' , the lower ends of these tubes fit upon solid fulcrum arms c^x , c^x , which are pivotally attached to the side members a , a^x .

R, R, are reservoir members containing 35 chambers r , r , for holding the water or other liquid to be fed to the brush B. These reservoir members rest on flanges a^6 , a^6 , on the lower inner edges of the side members a , a^x , as well as upon the extensions a^4 , a^4 , thereof, 40 the reservoir members being formed with external lugs r' , r' , for this latter purpose. Together the reservoir members form an arched casing for the operative parts both above and below the platform b, and those 45 mounted on the inner sides of the side members a , a^x . Their upper portions are formed with abutting walls r^2 , r^2 , and these are held together medially by the funnel F, which is formed with an inverted U shaped cross 50 member f, which straddles said upper walls r^2 , r^2 , as shown particularly in Fig. 5,—the upper portion of each reservoir being formed with a flanged opening r^3 , r^3 , for the accommodation of the sides of the funnel F. 55 The lower portions of the reservoir members R, R, are formed with splash receptacles r^4 , r^4 , adjacent to which are arranged the aprons d, d, interposed between said receptacles and the brush B, and inclined in 60 such manner as to act as conduits to the splash receptacles r^4 , r^4 , while shielding the adjacent advance floor surface.

The reservoir sections R, R, fit snugly between the side members a , a^x , and help to 65 reinforce and sustain them in position, coun-

teracting any tendency of the side members to lateral deflection in use, and helping to maintain a rigid structure.

When it is desired to remove the reservoir sections R, R, the funnel F, is lifted clear of the walls r^2 , r^2 , when the said sections R, R, may be readily lifted from their supports on the side members a , a^x , to give access to the operative parts, empty the splash receptacles, or for other reasons. They may be 75 thus removed or replaced without disturbing the other parts of the apparatus.

In the modification shown in Fig. 8, the reservoir sections R^9 , R^9 , are united in one integral structure, with the exception of the 80 splash receptacles r^{44} , r^{44} , which in this case are made in the form of removable drawers which may be drawn out horizontally for the purpose of emptying and replaced without otherwise disturbing the reservoir sections. In this construction the funnel F^9 , is formed integral with the reservoir walls; and in either structure the funnel F, is provided with a straining screen f^9 , to eliminate from the liquid introduced any matter that 90 might clog the valves or sprinkling pipes. In this modification the central traction wheels a^2 , are omitted, the machine resting and traveling flat on the end traction rollers a^{31} , a^{31} , so marked to distinguish them from 95 the corresponding caster traction rollers a^3 , in the other figures.

The distributing valves v , v , are attached to the lower inner edges of the reservoirs R, R, adjacent to one of the side members 100 a , a^x , the latter a^x , being shown in the drawing as supporting the mechanism for actuating said valves. The latter communicate with their respective reservoirs, and with the perforated sprinkler pipes s, s, the distributing holes in which latter are arranged to shed the liquid between the aprons d, d, and the brush B, or against the latter as preferred,—said sprinkler pipes s, s, extending preferably the whole length of the brush B, 110 and being supported upon the under sides of the liquid chambers r, r, or adjacent thereto.

The distributing valves v , v , are shown more or less symbolically in the drawings 115 as formed each with a valve rod v' , held normally in raised position to close the valve by a spring v^2 . To depress the valve rod v' , open the valve, and admit liquid to the sprinkling pipe s, a spring plunger p, is provided, actuated in turn by a depression rod e, mounted upon and in the side lever c' . Each distribution valve v , v , is of course provided with its own spring plunger p, the upper ends of the two converging centrally so that when the plunger rods p, p, are in their normal raised positions their upper ends extend toward and are in line with the fulcrum c^2 , of said lever c' , as will be seen by reference more particularly to Fig. 7,— 130

the plunger rods being feathered in the upper bearings a^7 , a^7 , so as to prevent their turning therein, as indicated by the splines p' , p' , in said figure. Both the upper and 5 the lower bearings a^7 , a^7 , and a^8 , a^8 , are formed in lugs on the inner side of the side member a^8 , and maintain the lower ends of the plunger rods p , p , in alinement with the valve stems. A spring p^2 , on each 10 plunger rod p , is interposed between its lower bearing a^8 , and a collar p^3 , on the rod, said spring tending constantly to force the rod upward with the collar p^3 , resting against the under side of the upper bearing 15 a^7 ,—this being the normal position of the parts with the valve closed.

When the side lever c' , is turned to one side or the other of the machine resting upon one or the other of the shoulders a^5 , 20 a^5 , on the side member a^8 , the lower end e^8 , of the depression rod e , is in alinement with the inclined upper portion p^8 , of one or the other of the spring plungers p , as indicated by solid and dotted lines in Fig. 7, so that 25 the downward thrust of the depression rod e , in either reversed position will actuate the spring plunger p , on the then forward side of the machine to open the distributing valve v , on that side and dispense liquid 30 to the forward side of the brush.

The depression rod e , is formed with an off-set e' , at its lower extremity to straddle the top of the side member a^8 , and the reservoir members R , R , are recessed adjacent 35 thereto as shown at r^5 , Figs. 1, 2, and 4, to admit of the requisite swing of the side lever c' , from one side of the machine to the other as indicated by dotted lines in Figs. 5 and 7. The depression rod e , is shown in 40 detail in Fig. 9, by reference to which it will be seen that the main portion of the depression rod e , is contained within the upper tubular portion of the lever c' , the offset e' , protruding through a longitudinal 45 slot c^4 , therein, and that a spring e^2 , is interposed between the shoulder or cross bar e^3 , of the rod e , and the upper end of the solid fulcrum arm c^8 , forming the lower portion of the lever c' . This spring e^2 , tends 50 constantly to force the rod e , upward and maintain it in its normal position with the cross bar e^3 , of the offset e' , against the upper end wall of the longitudinal slot c^4 . In this position the lower end e^8 , of the depression rod e , will just clear the upper ends 55 p^8 , of the spring plungers p , when the lever c' , is swung back or forth, and when the lever c' , is at rest in either position, the lower extremity e^8 , of the depression rod e , 60 will thus be in position to immediately depress the spring plunger p , when it is itself depressed against the resistance of the spring e^2 . This depression is effected by pushing down the knob e^4 , on the upper end 65 of the rod e , which protrudes above the end

of the tube c' , which constitutes the main, upper portion of the side lever. So long as the lever e , is thus depressed it is obvious that the distribution valve v , will be held open and liquid will be supplied from the 70 tank r , through the sprinkler pipe s , to the brush. When the knob or button e^4 , is released the spring e^2 , will return the depression rod e , automatically to its normal position, releasing the plunger p , so that its 75 spring p^2 , will raise it until its collar p^3 , again contacts with the bearing lug a^7 , releasing the valve rod v' , and allowing its spring v^2 , to close the valve v , and shut off the liquid supply. By keeping the thumb 80 of one or the other hand in contact with the knob e^4 , it is obvious that the operator may control the flow of liquid at will, varying it more or less by opening or closing the 85 valve v , more or less, and shutting it off entirely for instance when the machine is standing still, or about to be reversed in direction of travel. For instance when the machine is pushed slowly over the surface to be cleaned less fluid will be required than 90 if traveling at a rapid rate of speed; and it may be desired to use the brush in a nearly dry state under certain conditions of use, as in polishing floor surfaces, &c. In fact the machine is practically a sweeper and 95 may be used as such, the degree of moisture imparted to the brush being only sufficient to lay the dust and insure its deposit in the splash receptacle r^4 .

Provision may be made for temporarily 100 locking the rod e , in its depressed position when desired, as where the machine is used in long halls or corridors and the flow of liquid is to be continuous and uniform. This may be accomplished by various well known 105 mechanical expedients, as by a pivoted lever or clasp e^5 , as illustrated in Fig. 10, or equivalent device,—the upward pressure of the spring e^2 , in the illustration shown in said figure being sufficient to maintain the engagement of the overlapping end of the clasp e^5 , with the button or knob e^4 , until the lever e^5 , is turned forcibly to release the depression rod. 110

The splash aprons d , d , are pivotally supported upon and between the side members a , a^8 , being formed at their ends with trunnions d' , d' , fitting in slots a'' , a'' , formed for their reception in the inner sides of said side members a , a^8 , as shown more particularly in Fig. 13. The aprons d , d , are concaved to conform approximately to the convexity of the cylindrical brush B ; and the bearing slots a'' , a'' , are elongated and inclined convergently toward the axis of the 125 brush, approximately at least, so that the aprons may be drawn into contact with the peripheral surface of the brush when it is desired to clean them, as for instance to prevent drip when the machine is stopped prior 130

to reversal, discontinuation of use, or like purpose. In other words, while the aprons d , d , rest normally out of contact with the brush, resting against the adjacent sides of the splash receptacles r^4 , or other stationary part, provision is made for bringing either of them into contact with the brush while the latter is in motion thereby causing it to clean the apron,—the apron to be subjected to this treatment being the advance apron, or one in front of the brush as the machine is propelled in either one direction or the other as the case may be,—it being remembered that the rotation of the brush B, is against the direction of travel as indicated by the arrow in Fig. 8, so that the rotating brush and centrifugal force will precipitate the splash over the apron and into the splash receptacle r^4 . Under these conditions it is evident if the apron is drawn into contact with the rotating brush all possible drip thereon will be wiped off into the receiver r^4 , and when the apron is again released, provided the discharge of fluid has been stopped in the interim, there need be no drip on the floor surface when the machine is brought to a stop. The contacting of either splash apron d , d , with the brush B, for the purpose above set forth may be effected in various ways, and I do not limit myself to the means shown and described herein although said means are simple and effective, consisting essentially of flexible connections h , h , one attached medially of the length of each apron d , from which it extends to, and is threaded over suitable guide pulleys h' , h^2 , h^3 , finally connecting with one arm of a rock lever i , fulcrumed in the side member a^x , and having an external crank arm i' , by which it may be rocked through the medium of another flexible connection i^2 , connected therewith and extending along the outer side of the lever c' , into convenient proximity to the handle, as illustrated in Fig. 3. Thus by pulling the cord or connection i^2 , the lever i , will be rocked sufficiently to lift the front apron into contact with the brush as and for the purpose before stated, and when the connection i^2 , is released, the apron by its own weight will fall back into its normal position, ready to perform its usual function, this return drop of the splash apron d , carrying with it the rock lever i , into position to be utilized in raising either splash apron as may be required in use. It will thus be noted that the inclined convergent bearing slots or recesses a'' , a'' , in the side members a , a^x , perform an important function in controlling and guiding the aprons under all conditions of use; and that the aprons may thus be manipulated without disturbance or interference with any other part of the apparatus, either operative or stationary.

65 The reservoir sections R, R, when cou-

pled together by the bifurcated funnel F, as hereinbefore described and as shown particularly in Fig. 5, constitute essentially a duplex reservoir or tank like unto the integral structure shown in Fig. 8, and may be 70 designated as such for convenience of description,—the only difference being that in Fig. 8, the duplex tank R, R, and the splash receptacle drawers r^4 , r^4 , are independently supported on the side members a , a^x , and removable separately.

The reversal of the handle c^3 , and side levers c , c' , also effects the reversal of the motor M, so that the rotation of the brush B, will be thereby changed also, to rotate against or opposite to the line of travel of the machine. This may be effected by a switch lever k , rigidly attached to the axis of the side lever c , and arranged to alternately open and close the electrical terminals in the switch box n, as the side levers c , c' , are changed from one position to the other. The electrical switch n, may be of any desired or well known form of double type of reversing switch, being here shown symbolically, as having the spring push buttons n' , n' , the depression of either one of which reverses the circuit in the motor. The service wires w , w , connected by the usual electrical cable and socket plug (not shown) with a service line as heretofore pass down through the side lever c , to and through its trunnion arm c^x , which is formed with the conduit c'' , for the purpose, and through the axial conduit c^{22} , in the trunnion c^{13} , which 100 axial conduit c^{22} , is extended through the trunnion to facilitate wiring. The cylindrical trunnion c^{13} , is journaled in the side member a , and is integral with the trunnion arm c^x , of the lever c . To its inner end is rigidly keyed the switch lever k , so as to rock therewith when the lever c , is reversed in position,—the presser fingers k' , k' , on said switch lever k , having the same spacing and inclination with relation to each other as that represented by the two positions of the side lever c , as will be readily understood by reference to Fig. 6, in which the reversed position is shown in dotted lines. The introduction of the loop service 110 wires w , w , axially through the trunnion c^{13} , affords the least possible disturbance of said wires when the levers c , c' , are reversed. In order to facilitate control of the motor M, a cut-off switch m^x , may be positioned on the handle c^3 , and interposed in a loop of one of the service wires made to extend through said tubular handle to said switch. Thus the full control of the apparatus is placed within convenient reach and control of the person propelling the same by means of the handle c^3 —i. e., the power through the cut-off switch m^x , and reversing switch k , the liquid supply through the button or knob e^4 , on the upper end of the de- 130

pression rod *e*, and the position of the splash aprons *d*, *d*, through the medium of the flexible connection *i*², and rock lever *i*. Furthermore it will be seen by reference particularly to Figs. 1, 2 and 3 of the drawings (Fig. 3, being essentially a duplicate of the other side of the machine, the only difference being the absence of the rock lever crank arm *i'*, and flexible connection *i*².)

5 that externally the apparatus is very plain, compact and unobtrusive,—there being practically no operative parts exposed and little or no protuberance beyond the contour or outline of the reservoir sections *R*, *R*, other than that of the side levers *c*, *c'*, and handle *c*³. In fact the apparatus is essentially and practically self-contained in the sense that substantially all the operative parts are isolated and protected from contact with extraneous objects, and this is an important feature in apparatus of this class. It not only affords protection and long life and service in so far as the machine is concerned, but it also obviates the danger of damage

10 to walls, furniture, &c., during the use of the machine, and adapts the latter for use in spaces and under conditions affording comparatively limited area for manipulation.

The elimination of drip from the splash

15 apron when the machine is stopped is also an important factor in practical use, since the stoppage for reversal of travel or other purpose has heretofore inevitably resulted in a line of dirty drip deposited by the forward apron upon the floor or other surface under treatment, and when going in the opposite direction the drip from the rear apron would drop on the floor behind the brush, which drip had to be wiped up or otherwise removed by hand.

Another distinctive feature of my present construction as compared with that disclosed in my concurrent application hereinbefore referred to is that in the present case 20 the motor, tanks, splash receptacles, &c., are not supported upon the reversing levers and do not have to be lifted over thereby in reversing the direction of travel. Hence less labor is involved in the use of the machine, so that it may be conveniently and successfully operated by minors and females, being thereby more fully adapted for domestic use as well as for public buildings and institutions. It is also more simple and inexpensive in construction, more durable, and less liable to derangement, or to require readjustment. And in this respect the mounting of the motor and brush and intermediate connections on one adjustable part 25 or platform simplifies the adjustment for the purpose of compensating for the wear of the brush.

What I claim as my invention and desire to secure by Letters Patent is,

65 1. In apparatus of the character design-

nated, the combination of side members, traction rollers mounted thereon, a platform vertically adjustable upon and between said side members, a motor, a rotatable brush, intermediate means for transmitting power from the motor to the brush all mounted and supported on said adjustable platform, duplex fluid-containing means upon opposite sides of said platform.

2. In apparatus of the character designated, the combination of side members, traction rollers mounted thereon, a platform mounted upon and between said members by means which admit of its vertical adjustment thereon, a motor and a rotatable brush mounted on said adjustable platform in fixed relation to each other, intermediate means for transmitting power from said motor to said brush, duplex fluid-containing means upon opposite sides of said platform.

3. In apparatus of the character designated, the combination with the side members, connecting intermediate platform, and motor and brush mounted thereon, said platform being vertically adjustable, of a duplex fluid reservoir removably supported upon said side members and straddling the platform and operative parts, for the purpose described.

4. In apparatus of the character designated, the combination with the side members, connecting intermediate platform, and motor and brush mounted thereon, of a duplex fluid reservoir made in two tank sections removably supported on said side members, and formed with abutting upper side walls, for the purpose described.

5. In apparatus of the character designated, the combination with the side members, connecting intermediate platform, and motor and brush mounted thereon, of a duplex fluid reservoir made in two tank sections removably supported on said side members and formed with abutting upper side walls, and a bifurcated funnel straddling said upper side walls and coupling the two tank sections together, for the purpose described.

6. In apparatus of the character designated, the combination of a cylindrical brush, means for rotating the same, a splash apron arranged in conjunction with said brush to conduct the splash to a receptacle, said receptacle, and means for temporarily lifting and holding the splash apron against the periphery of the brush, for the purpose described.

7. In apparatus of the character designated, the combination of a cylindrical brush, means for rotating the same, a splash apron loosely mounted and arranged in conjunction therewith to conduct the splash to a receptacle, said receptacle, a flexible connection attached at one extremity to the apron and at the other to a bell crank lever,

and means for rocking the latter, for the purpose described.

8. In apparatus of the character designated, the combination of a cylindrical brush, a splash apron interposed between said brush and said receptacle and formed with end trunnions loosely mounted in elongated slot bearings in the side members of the frame, said bearing slots being inclined 5 upward toward the axis of the brush, a flexible connection attached at one end medially to the splash apron and at the other to a bell crank lever, and means for rocking the latter, for the purpose described.

15 9. In apparatus of the character designated, the combination of a cylindrical brush, means for rotating the same, splash receptacles on either side of said brush, splash aprons interposed between said brush 20 and said receptacles, each apron formed with end trunnions loosely mounted in elongated slot bearings in the side members of the frame, said bearing slots being inclined upward toward the axis of the brush, flexible 25 connections medially attached to the aprons and connecting them with a rock lever common to both, and means for rocking said lever, whereby the aprons may be alternately brought into contact with the 30 periphery of the brush, for the purpose described.

10. In apparatus of the character designated, the combination of a cylindrical brush, a motor for rotating the same, liquid 35 reservoirs mounted one on each side of said brush and motor, a distributing valve and sprinkler pipe for each reservoir, spring plungers arranged to control the action of said valves, a lever pivoted medially be- 40 tween said spring plungers, and a depression rod mounted on said lever and adapted to operate said spring plungers alternately for the purpose described.

11. In apparatus of the character designated, the combination of a cylindrical brush, a motor for rotating the same, liquid 45 reservoirs, one mounted on either side of said brush and motor, a distributing valve and sprinkler pipe for each reservoir, spring 50 plungers arranged to control the action of said valves, a lever pivoted medially between said spring plungers, a depression rod mounted on said lever and adapted to operate said spring plungers, a spring which 55 tends to hold said depression rod in its normal retracted position, and a clamping device for holding said depression rod down temporarily against the resistance of said spring, for the purpose described.

60 12. In apparatus of the character designated, the combination of side members, a

cylindrical brush, an electrical motor for rotating the same, mounted between said side members, liquid reservoirs mounted one on each side of said brush and motor, 65 a distributing valve and sprinkler pipe for each reservoir, spring plungers arranged to control the action of said valves, a lever pivoted on one side member medially between said spring plungers, a depression rod 70 mounted on said lever and adapted to operate said spring plungers alternately, a spring which tends to hold said depression rod in its normal retracted position, a lever pivotally connected to the opposite side 75 member in axial alinement with the first mentioned side lever and connected therewith by a cross handle bar, and a reversing switch actuated by said second lever to reverse the electric motor simultaneously with 80 the reversal of the liquid supply, for the purpose described.

13. In apparatus of the character designated, the combination of side members, a cylindrical brush, an electric motor for rotating the same mounted between said side members, liquid reservoirs mounted on said side members, one on each side of said brush and motor, a distributing valve and sprinkler pipe for each reservoir, spring plungers arranged to control the action of said valves, a lever pivoted on one side member medially between said spring plungers, a depression rod mounted on said lever and adapted to operate said spring plungers, a 85 spring which tends to hold said depression rod in its normal retracted position, a lever pivotally connected to the opposite side member in axial alinement with the first mentioned lever and connected therewith by 90 a cross handle bar, and a reversing switch actuated by said second lever to reverse the electric motor simultaneously with the reversal of the liquid supply, and a cut-off switch on 95 said cross bar handle interposed in the electric service circuit, splash receptacles on either side of the brush, splash aprons movably supported and interposed between said splash receptacles and the brush, flexible connections connecting said splash aprons 100 with a common bell crank lever, and an operative connection extending from said bell crank lever along one side lever into proximate relationship to the said cross bar handle whereby the operation of the apparatus may be completely controlled by an operator at the handle of the machine, for 105 the purpose described.
